UNITED STATES PATENT OFFICE.

HARRY WARD LEONARD, OF BRONXVILLE, NEW YORK.

ELECTRIC-CIRCUIT CONTROLLER.

No. 914,356.

Specification of Letters Patent.

Patented March 2, 1909.

Original application filed November 30, 1901, Serial No. 237,653. Divided and this application filed April 6, 1906. Serial No. 310,200.

To all whom it may concern:

Be it known that I, HARRY WARD LEONARD, a citizen of the United States, residing at Bronxville, in the county of Westchester and State of New York, have invented certain new and useful Improvements in Electric-Circuit Controllers, of which the following is a full, clear, and exact specification.

This application is a division of my pending application filed November 30, 1901, Serial No. 84,188, renewed December 20, 1904, Serial No. 237,653, granted April 10, 1906, Patent No. 817,719, and relates generally to controlling switches and has a particular application to motor starting rheostats, or rheostats employed with electric motors or other electrical translating devices, in which the resistance is employed not for regulating the energy supplied to the motor or other translating device, but mainly for gradually raising the energy at the terminals of the translating device to the full electromotive force.

My invention is also of importance where regulating resistances are used and to prevent their improper operation.

I have found in practice that such rheostats are frequently damaged by holding or permitting the contact lever to remain on the initial or starting contact or contacts near the same with all the resistance of the rheostat or a considerable portion thereof in circuit. I have also found that operators frequently close the circuit at the initial or starting contact of the rheostat and then return the lever to the idle position, thus drawing an arc at the initial contact. This also damages the rheostat. I have also found that operators sometimes close the main circuit when the resistance controlling device, which might be used as regulator, is in an intermediate position. This of course allows an excessive and damaging flow of current.

The main object of my invention is to devise a starting rheostat or controller, or to provide the present type of rheostat with a controlling device, which will prevent this improper handling of such rheostats.

Although of importance in connection with hand controlled rheostats, my invention is also of advantage in connection with automatically operated rheostats.

The full torque current is the current which the motor takes in developing its full

rated horse-power. In starting any motor, it becomes necessary to produce a torque larger than that due to the full torque current because the motor and the load have to be accelerated, and during the period of acceleration, a larger current will be required than that necessary after the motor has been accelerated to full speed. In the manufacture of motor starting rheostats, it is common practice to have such a resistance in the rheostat that the current which will flow when the motor is at rest and the first contact is made at the rheostat, will be fifty per cent. larger than the current taken by the motor when producing its normal full torque. In other words, this starting accelerating current is fifty per cent. larger than the full torque current, that is, it is one hundred and fifty per cent. of the full torque current.

In order to prevent the burning at the initial contact of the rheostat, due to the closing of the circuit upon insufficient surface, or due to the backward movement of the contact lever after making the first contact, which results in the formation of an arc due to the full electromotive force and one hundred and fifty per cent. of the full torque current (when the motor has no counter electromotive force), the rheostat should be provided with an auxiliary switch, by which the circuit is quickly closed upon an ample surface and which switch will open the circuit with a snap-action when the contact lever is returned to the initial position. This auxiliary switch should be beyond direct hand control in opening and may be mechanically or electrically controlled by the rheostat contact lever or controlling switch.

In my original application, I have disclosed two forms of my invention in which the auxiliary switch is mechanically controlled. The present application relates more particularly to forms in which the control of the auxiliary switch is by electrical means.

My invention includes various other improvements and advantages which will be understood from the following description and accompanying drawings.

In the accompanying drawings, Figure 1 is a diagrammatic view of one form of my invention; and Fig. 2 is a similar view of another form of my invention.

Referring to Fig. 1, there is mounted on a

suitable base (not shown) a series of contacts a , to which the sections of the resistance a' are connected. This resistance, it will be understood is arranged in any suitable manner beneath the base or within a casing, and the sections of resistance will be insulated from each other and in some instances provided with means for absorbing the local energy developed therein. B is a switch in the form of a rheostat contact lever pivoted on the base. P and N are the supply conductors, and the translating device controlled is indicated as a motor M. The auxiliary switch is indicated by the reference character C. This is in the form of a pivoted knife switch blade; c, c' are contact jaws, as in Figs. 1 and 2 of my original application; D is an actuating hammer for the switch C, and in this instance is started by solenoids O and O' whose cores are connected to the arms of the hammer, and d^5 is the spring for throwing the hammer after it passes the center of equilibrium, although in this arrangement the spring might be dispensed with, since the movement of the cores will be very rapid and move with increasing speed. The circuit connections are from conductor P to switch C, to lever B, resistance a' and motor M to the conductor N, the field of M being in shunt from lever B around the resistance and motor armature. Coils O and O' are connected in shunt relation between contacts o and o' and conductors P and N. Contacts o' and o are located adjacent to the first and second rheostat contacts a respectively, so that in the initial position lever B will bridge the first contact a and contact o' , and in the second position contact o and the second contact a will be bridged. The effect of this, is to connect either coil O' or O in circuit and as shown coil O is in circuit and its core is drawn down and hammer D is tilted to the right closing switch C. If lever B is returned to its initial position, coil O will be cut out and coil O' cut in, thus actuating the core of the latter to throw the hammer to the left and open switch C. When lever B is moved to its final position, both coils will be cut out of circuit and spring d^5 will hold switch C in position. It is thus apparent that the main circuit will be completed, and that the main current flow will be interrupted at the auxiliary switch C, and the sparking which would otherwise take place at the resistance contacts is avoided. A modification of this arrangement is shown in Fig. 2. Here only one coil O² is employed, and this coil is connected between conductor P and a contact o^2 with which the insulated short arm b^2 of lever B makes contact when in contact with any of the rheostat contacts a from the second to the final contacts, but not when in contact with the initial contact. Switch C (shown as a brush switch) is provided with a rod z which breaks the arc on carbon contacts

z'. This switch is mounted on a vertically sliding rod z^2 provided at its upper end with a stirrup z^3 within which works a foot o^3 secured to the lower end of rod o^4 projecting from the core or plunger of coil O². The vertically sliding rods z^2 and o^4 work in suitable guides, and the lower end of rod z^2 is rectangular and works in a correspondingly shaped bearing to hold switch C in alinement with its stationary contacts.

As shown in Fig. 2, the rheostat lever B is in its second position, and the circuit to coil O² is closed and its core is drawn up and switch C is closed. If now the operator returns lever B to the initial position, coil O² will become demagnetized and its plunger will drop striking a blow to the stirrup, the force of which and the tension of the brush switch, will drive the switch downward and open the circuit to the rheostat and motor. When the lever B is moved forward, closing the circuit again at contact o^2 , the plunger of coil O² will rise, and through the engagement of foot o^3 and stirrup z^3 , switch C will be closed.

It will be noted that I have indicated a motor M in the drawings having a shunt field winding, and that the supply circuit to both the armature and shunt winding is opened by means of the automatic switch in the main circuit. Also, that when the circuit is opened, the armature and field are closed on themselves, giving a closed circuit for the field discharge.

It is evident that my invention may be embodied in various forms of construction and that I am not limited in the scope thereof except as indicated in the following claims.

Having thus described my invention, I declare that what I claim as new and desire to secure by Letters Patent, is—

1. The combination of a rheostat, a switch, an electro-magnetic actuating device therefor, and means whereby said switch is closed and opened by the forward and backward movement of the movable element of said rheostat at the initial positions.

2. The combination of a hand operated electric switch, a second switch in series therewith, means for automatically moving said second switch to the closed or to the open position comprising electrical controlling means operated by the movement of said hand operated switch.

3. The combination of a rheostat having a movable element for controlling the resistance, a switch in series therewith, means for moving said switch to the closed or open position, and electrical contact means controlled by the position of said element for controlling said switch moving means.

4. The combination with a rheostat having a movable element for controlling the resistance, of a switch in circuit therewith, an electro-magnetic actuating device for said switch, and means whereby said switch is

- closed to complete the circuit and opened to interrupt the current flow by the forward and backward movement of said element at the limiting positions.
5. The combination of a motor rheostat having a movable element for controlling the resistance, a switch in series therewith, means for moving said switch to the closed or open positions, and electrical contact means controlled by the position of said element for causing said switch moving means to actuate said switch and complete the circuit and to cause the opening of said switch to interrupt the current flow.
10. 6. The combination of a motor rheostat, a switch for closing the circuit, a control magnet governing its closure, and means for controlling the circuit connections of said magnet dependent upon the return of the resistance controlling element of said rheostat to the initial position.
15. 7. The combination of a motor rheostat having a movable element for controlling the resistance, a circuit breaker, a contact engaged by the movement of said element, a coil in circuit with said contact and controlling the closing of said circuit breaker, and circuit connections whereby said coil is deenergized after said circuit breaker has been closed.
20. 8. The combination of a motor rheostat having a movable element for controlling the resistance, a circuit breaker, a contact engaged by the movement of said element, a coil in circuit with said contact and controlling the closing of said circuit breaker, and means whereby after said circuit breaker has been closed the circuit of said coil may be opened without affecting said circuit breaker.
25. 9. The combination of a supply circuit, an electric motor, a switch for connecting and disconnecting the motor armature to and from the supply circuit, electromagnetic means for actuating said switch to connect and disconnect said motor armature to and from the supply circuit, and means whereby said electromagnetic means is automatically deenergized during normal operation of said motor.
30. 10. The combination of a translating device, a controlling switch, an electromagnetic winding for effecting the closure of said switch when said winding is energized, means for holding said switch closed independently of said winding, after the switch has been moved to closed position, and means whereby the current in said winding is reduced after the closure of said switch.
35. 11. The combination of a resistance having a movable element for varying the resistance, a switch, a coil controlled by the movement of said element for controlling the closure of said switch, and a second coil controlled by the movement of said element for controlling the opening of said switch.
40. 12. The combination of a resistance having a movable element for varying the resistance, a switch, electromagnetic means for closing said switch, means controlled by the movement of said element for interrupting the circuit of said electromagnetic means, and auxiliary means for holding said switch closed.
45. 13. The combination of an electric motor, an armature resistance, a switch in series with said resistance, a coil for closing said switch automatically, a second coil for automatically opening said switch, and means for insuring the automatic closure of said switch only when a protective amount of resistance is in series with the motor armature.
50. 14. The combination of an electric motor, a switch in series with the motor armature, two actuating coils for controlling the automatic movement of said switch, one of said coils being energized during the closing of said switch and the other of said coils being energized during the opening of said switch, and additional means for maintaining said switch closed.
55. 15. The combination of a supply circuit, an electric motor, an automatic switch in series with the motor armature, a coil for controlling the automatic closure of said switch, and connections whereby said coil is connected in series with the motor armature across the supply circuit during the closing period of said switch whereby said coil is subjected to the electromotive force of the supply circuit less any counter electromotive force of the motor armature.
60. 16. The combination of an electric motor, an armature controlling rheostat, an electromagnetically controlled automatic switch, means for controlling the closing movement of said switch by the movement of the movable element of said rheostat when moved in the resistance inserting direction, and means controlled by the movement of said element for causing the automatic opening of said switch.
65. 17. The combination of a supply circuit, an electric motor, an armature resistance, a switch having a coil for closing the switch, and means whereby said coil is connected in series with the motor armature and said resistance across the supply circuit to effect the automatic closure of said switch and whereby the said coil is shunted when said switch is closed.
70. 18. The combination of a switch, an electromagnetic coil for automatically moving said switch, connections whereby said coil is shunted after the movement of said switch, and mechanical means for holding said switch in closed position.
75. 19. The combination of a controlling resistance, a constant electromotive force supply circuit, an electromagnetic winding, a switch controlled by said winding, and means

for connecting said winding in series with said resistance across said circuit and for connecting said switch in series with said resistance and in shunt with said winding.

5 20. The combination of a constant electromotive force supply circuit, an electric motor, a switch in series with the motor armature, an electromagnetic winding for controlling said switch, a second switch adapted 10 to connect said winding in series with the motor armature across said circuit, and means whereby said first named switch is connected in shunt to said winding.

21. The combination of a constant electromotive force supply circuit, an electric motor, a controlling resistance therefor, an electromagnetic winding, a switch controlled by said winding and adapted to be connected in series with the armature of said motor and 15 in shunt with said winding, and means for connecting the motor armature, said resistance, and said winding in series across the supply circuit.

22. The combination of a constant electromotive force supply circuit, an electric motor, a controlling resistance therefor, an electromagnetic winding, a switch whose closing movement is controlled by said winding and which switch is adapted to be 25 connected in series with the motor armature and said resistance and in shunt with said winding, and means for connecting said motor armature, said resistance, and said winding in series across the supply circuit.

23. The combination of a constant electromotive force supply circuit, an electric motor, an armature resistance, a manually operated switch, an electromagnetic winding, connections for connecting the motor armature, said resistance, said switch, and said winding in series in a branch circuit across said supply circuit, an automatic switch 40 automatically closable through the agency of said winding, and connection whereby said automatic switch, the motor armature, and 45 said resistance are connected in series with each other and whereby said automatic switch is connected in shunt with said winding.

50 24. The combination of an electric motor, a supply circuit of constant electromotive force, a manually operated rheostat, a switch, said switch and rheostat being in series with each other and with the motor armature 55 across said circuit, and electrical means controlled by the movement of the movable element of the rheostat for controlling the closing and opening of said switch to establish and break the current through the motor armature.

60 25. The combination of an electric motor having a field winding energized independently of its armature current, a manually operated rheostat for controlling the motor armature, a switch for carrying both the

motor armature current and the current through said field winding, and electrical means controlled by the movement of the movable element of said rheostat for causing the automatic closing and opening of said 70 switch.

26. The combination of a supply circuit of constant electromotive force, an electric motor, an armature controlling rheostat, said rheostat, the motor armature and a field winding of the motor being connected in a closed circuit, a magnetically moved switch for making and breaking connection between said closed circuit and the supply circuit, and electrical means dependent upon the movement of the movable element of the rheostat 75 for controlling the opening movement of said switch.

27. The combination of a rheostat having a movable element for controlling the resistance, an automatic switch in series therewith, and electrical means operated by the movement of said element for controlling the automatic closing and automatic opening 80 of said switch.

28. The combination with a supply circuit, of a resistance having a manually movable element for varying said resistance, a switch in series therewith, and electrical means for controlling the closing and opening of said switch, said means being controlled by said movable element whereby said switch is closed when said element is manually moved in a direction to reduce resistance and is opened when said element is 90 moved in a direction to increase resistance.

29. The combination of a resistance having a manually movable element adapted to vary the resistance, a switch for controlling the circuit of said resistance, and electric 105 means for controlling the automatic closing and automatic opening of said switch, said means being controlled by the movement of said movable element.

30. The combination of a motor, a rheostat for said motor having a manually movable resistance varying element, an automatic electromagnetic switch, and electric means for causing the manual movement of 110 said element to control the movement of said switch in two directions at the starting position.

31. The combination of a motor, a rheostat for said motor having a movable resistance varying element, means for causing 115 an auxiliary electrical contact to be made by the movement of said element to a certain position and to be broken by its movement in a direction to insert resistance, an electro-responsive winding energized independently 120 of the motor operating current and the current in which is affected by the making and breaking of said contact, and a switch in series with the motor armature controlled by 125 said electroresponsive winding.

32. The combination of a circuit controlling rheostat having a movable resistance varying element, means for controlling the making of an auxiliary electrical contact by the movement of said element in a direction to reduce said resistance and for controlling the breaking of said contact by its movement in the opposite direction, an electro-responsive winding the current in which is affected by the making and breaking of said contact, and a switch the closing movement of which is controlled by said winding. 70
33. The combination of an electric motor, a controlling rheostat having a manually controlled element, a switch in series with said rheostat, and electrical means controlled by said element when moved in a direction to insert and in a direction to cut out resistance for causing the opening and closing of said switch independently of the rate of movement of said element. 75
34. The combination with a rheostat and a movable element for varying the resistance, of a switch for controlling the circuit of said rheostat, and electrical means operated by said element when moved in a forward and backward direction for respectively controlling the closing and opening movement of said switch. 80
35. The combination of a resistance controlling movable element, a switch in series therewith, and electrical means operated by the movement of said resistance controlling element for controlling both the automatic closing and automatic opening of said switch. 85
36. The combination of a rheostat having a manually movable element for varying the resistance, a switch for controlling the circuit to said rheostat, and electrical means operated by said element for controlling both the closing and opening movement of said switch when said element is in position to insert substantially all of said resistance. 90
37. The combination of an electromotive force producing device, an automatic switch whose automatic movement is dependent upon a current other than the current passing through said device, a rheostatic movable element in series with said switch, and a manually controlled auxiliary contact device functionally related to said element for controlling the automatic closing and automatic opening of said switch. 95
38. The combination of a rheostat having a movable element for varying the resistance, a switch in series therewith, restraining means for holding said switch in closed position, and means controlled by said element when substantially all of the resistance is in circuit for electrically closing said switch. 100
39. The combination of a rheostat having a movable element for varying the resistance, an electromagnetic switch in series therewith, restraining means for holding said 105
- switch in closed position, and electric means operated by said element at its initial position for closing the circuit of the controlling magnet of said switch and thereby controlling the closing of said switch. 110
40. The combination of an electric motor, a resistance having a movable element for controlling said resistance, an automatic circuit breaker in the motor circuit, a control coil for the circuit breaker energized independently of the motor current, and a contact at or near the initial position of said element for energizing said coil. 115
41. The combination of a resistance controlling current carrying movable element, said element being adapted to vary the amount of resistance in circuit but not adapted to interrupt the flow of current, a switch in series with said element adapted to open and close the circuit, and electromagnetic means functionally related to said element for controlling the automatic closing and automatic opening of said switch. 120
42. The combination of an automatic switch comprising two actuating coils, a circuit controlling movable element in series with said switch, and means dependent upon the movement of said element for selectively energizing said coils. 125
43. In combination, a motor controller, a switch, and means for automatically closing and opening said switch, said means comprising a magnet for opening said switch to control the motor circuit, and connections whereby said magnet is energized only when the controller is moved backward to a certain position. 130
44. In combination, a motor controller, a movable circuit controlling element, and means for automatically moving said element in both directions, said means comprising a magnet for controlling said element, and means whereby said magnet is energized only when the controller in its backward movement reaches a predetermined position. 135
45. In combination, a controller for an electric motor, a switch through which the motor current is supplied when the controller is in a predetermined position, and means for automatically closing and automatically opening said switch comprising a magnet for opening said switch, and means whereby said magnet is energized only when the controller in its backward movement reaches a predetermined position. 140
46. The combination of a rheostat having a movable element for controlling the resistance, an electromagnetic switch in series therewith, manually controlled auxiliary electric contact means functionally related to said element for controlling the automatic closing movement and automatic opening movement of said switch, said automatic closing movement being dependent upon the 145

movement of said element to a protective position.

47. The combination of an electric motor, an armature controlling rheostat, an electro-
5 magnetically controlled automatic switch, means for controlling the closing movement of said switch by the movement of the movable element of said rheostat when moved in the resistance inserting direction, and auxiliary electric contact means functionally related to said element for causing the automatic opening of said switch.

48. The combination of a motor, a motor controller having a movable element manu-
10 ally movable in both directions, a movable circuit closing element, means for auto-
15

matically moving said element to close its circuit, said means comprising a magnet for controlling the closing movement of said element, and means whereby said magnet is 20 energized to cause the closure of said element only when the controller in its backward movement reaches a predetermined position, the connection of said closing coil being such that said coil is energized independently of the motor armature current. 25

In testimony whereof, I affix my signature in the presence of two witnesses.
